Inventor.

Charles Louis Marti.

UNITED STATES PATENT OFFICE.

CHARLES LOUIS MARTI, OF EAST ORANGE, NEW JERSEY, ASSIGNOR TO MARTIAN MANUFACTURING CO., INC., OF NEWARK, NEW JERSEY, A CORPORATION OF NEW JERSEY.

TUNING COIL.

Application filed December 1, 1922. Serial No. 604,424.

To all whom it may concern:

Be it known that I, CHARLES LOUIS MARTI, a citizen of the Republic of Switzerland, and a resident of the city of East Orange, county of Essex, and State of New Jersey, have invented a new and useful Improvement 5 in Tuning Coils, of which the following is a specification.

The object of my invention is to afford 10 a support of adjustable length upon which operates the means employed for contact with the tuning coil, enabling it to fit various lengths of tuning coils without requiring it to be specially fitted.

15 I accomplish my results as follows:

Fig. 1 is a longitudinal elevation of a tuning coil embodying my improvement and Fig. 2 a cross section thereof. To posts *a* are fastened coiled springs *b*, on which slides 20 crosspiece *c*, containing the screw *d*, the point *e* of which contacts with the tuning coil *f*.

It will be seen that the coiled springs may be readily stretched to span the length of 25 the tuning coil. I preferably employ the

coiled springs to afford the adjustable support, though other adjustable means may be provided. The coiled springs also permit of lateral as well as longitudinal movement of the contact element, allowing of a wide area 30 of contact with the tuning coil and permitting of a more sensitive adjustment of the contact point.

I claim:

1. The combination, with a tuning coil, of 35 means of contact with the tuning coil and an elastic support upon which the means of contact is slidably mounted.

2. The combination, with a tuning coil, of 40 means of contact with the tuning coil and an elastic support upon which the means of contact is slidably mounted, said elastic support permitting lateral and longitudinal movement of the contact means.

3. The combination, with a tuning coil, of 45 means of contact with the tuning coil and a coiled spring support upon which the means of contact is slidably mounted.

CHARLES LOUIS MARTI.
